(57) **CLAIM**

The ornamental design for an elevated hub for a back roller, as shown and described.

DESCRIPTION

FIG. 1 is a top perspective view for an elevated hub for a back roller showing my new design;

FIG. 2 is a front side view, the back side view being a mirror image thereof;

FIG. 3 is a right side view, the left side view being a mirror image thereof;

FIG. 4 is a top plan view, the bottom plan view being a mirror image thereof;

FIG. 5 is an exploded view thereof;

FIG. 6 is an top perspective view shown in an environment of use; and,

FIG. 7 is a top perspective view with alternate hubs having skinned ends.

The broken lines in FIG. 6 depict environmental subject matter of a back roller used with the invention and forms no part of the claimed design.
